UNITED STATES PATENT OFFICE.

WILLIAM G. KENDALL, OF NEWARK, NEW JERSEY.

DESIGN FOR A CLOSURE FOR TALCUM-POWDER CANS.

52,992.

Specification for Design.

Patented Feb. 11, 1919.

Application filed September 18, 1918. Serial No. 254,682. Term of patent 14 years.

To all whom it may concern:

Be it known that I, WILLIAM G. KENDALL, a citizen of the United States of America, residing at Newark, in the county of Essex and State of New Jersey, have invented a new, original, and ornamental Design for a Closure for Talcum-Powder Cans, of which the following is a specification, reference being had to the accompanying drawing, forming part thereof.

In the drawings—

Figure 1 is a perspective view of a closure for talcum powder cans showing my new design;

Fig. 2 is a side elevation.

I claim:

The ornamental design for a closure for talcum powder cans, as shown.

WILLIAM G. KENDALL.
